6 Claims. (Cl. 178—66)

This invention relates to high-speed code transmission utilizing phase shift, and in particular a phase discrimination carrier communication system by the so-called phase shift system wherein sinusoidal or cosine waves are used to convey the data of the independent channels.

One object of this invention is to provide a high speed code transmission system, utilizing phase shift, wherein carrier wave phase synchronization is achieved between the send and receive station.

Another object of this invention is to provide an improved multi-channel telegraph system whereby the bandwidth necessary to transmit and receive a pair of channels is considerably reduced.

Of the three equi-spaced phase vectors of an ordinary carrier wave, this invention uses two split-phase carrier waves for two channels and the other split-phase carrier wave for phase synchronization. The amplitude of the transmitted wave is always constant, and a stably synchronized carrier wave is reproduced at the receiving end regardless of the obstacles in the transmission channel.

The above mentioned and other features and objects of this invention and the manner of attaining them will become more apparent and the invention itself will best be understood by reference to the following description of an embodiment of the invention with several alternative arrangements of parts taken in conjunction with the accompanying drawings wherein:

FIG. 1(a), (b), (c), (d), and (e) shows vector diagrams of the inventive concept;

FIG. 2(a) and (b) is schematic block diagrams of the send and receive circuitry respectively;

FIG. 3 shows an alternative arrangement of the relays in the output stage of the receiver (FIG. 2b);

FIG. 4 illustrates an alternative arrangement for the modulators of the transmitter (FIG. 2a);

FIG. 5(a) and (b) shows an alternative arrangement for generating the three phase vector carrier wave;

FIG. 6 illustrates an alternative arrangement in the receiver (FIG. 2b) using two sets of balanced modulators; and

FIG. 7 shows an alternative arrangement in the receiver for evaluating the condition where the receiving current is zero.

FIG. 1(a) shows the three-phase vector diagram of an ordinary carrier wave; i_0 , i_1 , and i_2 represent the zero phase, the $2\pi/3$ phase, and the $4\pi/3$ phase vector, respectively. Let i_1 and i_2 be the two-channel carrier waves, which are independently modulated with digital code information of the amplitudes 1 and 0. If i_0 is always transmitted, it is obvious, from the nature of the three-phase vectors, that the transmission vector becomes $i_0+i_1=-i_2$ (when i_1 is present) or $i_0+i_2=-i_1$ (when i_2 is present) as shown by (b) and (c) of FIG. 1 and that the magnitudes of the latter vectors are equal to $|i_0|$.

If neither i_1 nor i_2 is transmitted, the transmitted vector is obviously the i_0 carrier wave itself. As will be described later, this is utilized to generate the correct synchronizing carrier wave.

Since $i_1+i_2+i_0=0$, the transmitted vector would be zero and no carrier wave would be sent during the simul-

2

taneous communication of i_1 and i_2 . Therefore, in this case, no distinction could be made at the receiving end whether the transmission channel is faulty or busy. However, if a fourth vector $i_3=-i_0$, a vector having the reversed phase of i_0 , such as shown in FIG. 1(d) transmitted, the magnitude of the transmitted vector would always be same as $|i_0|$ whether during communication or not. Consequently a D.C. output of constant amplitude is obtained only when the synchronizing carrier wave at the receiving end is in phase with i_0 , and the output will be on-off when it is in phase with either vector i_1 or i_2 . Conversely, when the received wave is demodulated by a synchronizing carrier wave of any phase a constant output of magnitude is obtained, it means that the phase of that carrier wave is either in phase or in reverse phase with i_0 of the sending end, and it follows that a completely synchronized carrier wave is reproduced. Although the system of this invention is applicable to general code communication systems such as telegraphy, PCM, and IDP, telegraph modulation will be explained in detail hereunder for convenience sake.

FIG. 2(a) shows a transmitting station embodying the features of this invention. An oscillator OSC generates the zero phase of the carrier wave f which in turn is divided into four branches. It is here assumed that all of these branches have the same transmission loss and that the phase-shift due to the modulator is practically zero. The carrier wave f is applied to the output through an attenuator ATT, by the branch (1); to a switch circuit M_3 for short-circuiting the input of (1) by the branch (2); to a modulator M_1 after being phase-shifted by $2\pi/3$ through a phase shifter PS_1 by the branch (3); and to a modulator M_2 after being phase-shifted by $4\pi/3$ through a phase shifter PS_2 for the branch (4). M_1 and M_2 are ordinary on-off modulators for telegraph usage; M_3 is an on-off circuit which when it receives the D.C. codes DC_1 and DC_2 (when two channels CH_1 and CH_2 are communicating simultaneously) short-circuits or opens two sets of variable impedances in the secondary side of a transformer T and consequently interrupts the carrier wave at ATT cutting off the output of the branch (1). In other words, while CH_1 and CH_2 are communicating simultaneously, only the wave of $2\pi/3$ and $4\pi/3$ phase, modulated by M_1 and M_2 are transmitted and the vector carrier wave i_3 which is given by $i_1+i_2=i_3=-i_0$ and shown in FIG. 1(d) is transmitted. The magnitude of this vector is equal to $|i_0|$.

While CH_1 and CH_2 are communicating individually since only one of the two variable impedances is in a short-circuited condition and the other is left at high impedance, M_3 is essentially under an open condition and the output of (1) is normally produced on the output side through ATT.

Therefore, it is obvious that, only the carrier wave of $2\pi/3$ phase (if only CH_1 is communicating), or only the carrier wave of $4\pi/3$ phase (if only CH_2 is communicating), passes through M_1 or M_2 and is added to the direct current carrier wave of (1), forming the modulated wave of the vector shown in FIGS. 1(b) or (6) by the dotted lines.

In other words, it is shown that, whether CH_1 and CH_2 are communicating or not, the carrier wave of the modulated wave is represented by one phase of the reverse phase of the three-phase vectors shown in FIG. 1(a). Therefore, the wave may be deprived of the unnecessary side band wave by BP_1 , amplified by an amplifier AM and sent to the transmission channel. The technical merits of this system lie in that, notwithstanding its phase shift modulation wave, the communication capacity is twice as large as that of a carrier communication system using the conventional dual side band transmission system.

that high speed communication is possible, and in addition the amplitude is constant and synchronism is surely stable.

Now the receiving end station of this system will be described with reference to FIG. 2(b), wherein the receiving wave is amplified to the required output level by an amplifier AMP_2 , and the required frequency passed by a band-pass filter BP_2 , and then divided into four branches.

Branch (3) is the synchronizing carrier wave generator circuits, (4) is the short-circuit switch circuit for (3) in FIG. 2(a), and (1) and (2) are demodulating circuits. One of the three phase carrier wave vectors is always applied with the same amplitude to the input of (3). If the frequency of the input carrier wave be multiplied by three and then by $\frac{1}{3}$ by the two-stage feedback ladder circuit consisting of modulators M_5 and M_6 , rectifiers K_1 and K_2 , and amplifiers AMP_3 and AMP_4 , it is apparent that, assuming the input wave to be

$$i = a_0 \sin \omega t + a_1 \sin \left(\omega t - \frac{2\pi}{3} \right) + a_2 \sin \left(\omega t - \frac{4\pi}{3} \right)$$

(zero phase carrier wave $\sin \omega t$)

here, as mentioned above, either one or two of a_0 , a_1 , are always zero, and $a_0 = a_1 = a_2$, the first stage triple frequency output due to M_5 and K_1 is, filtering out the higher unnecessary frequencies,

$$i' = a'_0 \sin 3\omega t + a'_1 \sin (3\omega t - 2\pi) + a'_2 \sin (3\omega t - 4\pi) \\ = a_1 \sin 3\omega t$$

that the $\frac{1}{3}$ demultiplied frequency output due to M_6 and K_2 is consequently of a constant amplitude and a constant and zero phase and is given by

$$i' = a'_1 \sin \omega t$$

Furthermore, it is well known that, if AMP_3 and AMP_4 are placed under oscillating conditions with their gains sufficiently large, the original oscillation phase is maintained, even if the input of (3) is interrupted for a short time.

Since the synchronizing carrier wave is given to demodulators D_1 and D_2 of the branches (1) and (2) through a variable phase shifter PS_3 , a reversing switch V and a 90° -phase shifter PS_4 , a constant positive or negative D.C. may be obtained, whether communicating not, by regulating the synchronizing carrier wave phase through PS_3 in conjunction with meter MET_3 (which reads D.C. output demodulated by D_2). When the above instant is achieved, PS_3 is in phase with the zero or phase of the transmitted carrier wave. If PS_3 is in phase with i_1 or i_2 , it follows that an interruption occurs, and if MET_3 is not constant. The meter MET_3 may be in the form of a high sensitivity D.C. meter, a pair of voltmeters indicating neon tubes, or the so-called magic eye indicator. If an ordinary D.C. meter is employed, the deflection will show 0.75 which is the mean value of one half and unity of the full scale, in response to zero phase carrier, whereas the deflection will show -0.125 which is half of the difference of 0.75 and unity, in response to π -phase carrier. Such deflection shows whether the receiving end station is in phase or not, as is described below. In any case, deflection of the meter MET_3 shows an operator that the carrier is being received by the receiving device. In case no deflection is produced in the meter MET_3 , the receiving end station is not receiving any carrier signal.

Thus, when PS_3 is determined, it is possible to discriminately operate the two relays REL_1 and REL_2 corresponding to CH_1 and CH_2 by using the carrier wave whose phase is shifted by $\pi/2$, and then demodulated by D_1 , and passing a D.C. code current in the circuits in which alternately reversed rectifiers R_1 and R_2 at the relays REL_1 and REL_2 respectively are connected in series, and to reduce a divided current at the local circuit.

The principle on which the synchronous demodulation is possible will be explained hereunder.

While i_1 and i_2 are communicating independently, the demodulated outputs i_5 and i_6 of D_2 due to the carrier wave in phase with or in reversed phase with i_0 in the circuit for generating the synchronizing carrier wave of (3) are

$$i_5 = \pm 2i_1 \sin \omega t = \pm 2a_1 \sin \left(\omega t - \frac{2\pi}{3} \right) \sin \omega t \\ = \pm a_1 \cos \frac{2\pi}{3} = \mp \frac{a_1}{2} \text{ (D.C. component only)}$$

and

$$i_6 = \pm 2i_2 \sin \omega t = \pm 2a_2 \sin \left(\omega t - \frac{4\pi}{3} \right) \sin \omega t \\ = \pm a_2 \cos \frac{4\pi}{3} = \mp \frac{a_2}{2} \text{ (D.C. component only)}$$

Both are simultaneously in phase or in reversed phase with the sending end D.C. code. Therefore, if the D.C. output due to D_2 is read with MET_3 while i_1 and i_2 are communicating independently, and if, for instance, SW is assumed to be in correct position for positive readings, then, if MET_3 is negative, the D.C. output of D_2 is reversed by reversing SW, to give the output of the phase shifter PS_4 the correct $\pi/2$ phase shift. Thus, a carrier wave of a correct phase is given to D_1 .

When i_1 and i_2 are simultaneously communicating a part of the code current on the relays REL_1 and REL_2 is taken out from terminals XY shown in the drawings, and applied to the corresponding terminals XY of a short-circuit switch M_7 of the branch (4) in view of the danger of the carrier wave of D_2 becoming in phase with i_3 , and with a view to cutting off the input of (3). This done, M_7 operates in the same manner as M_3 in the sending end to short-circuit the input of (3). Assume that AMP_3 and AMP_4 have large gains and are under a normal oscillation condition in phase with i_0 , the carrier wave having the previous phase impressed to D_1 as it is. This separates the next output of D_1 even though CH_1 and CH_2 may be obtained simultaneously. The demodulated output i_5 and i_6 due to D_1 become as follows, due to the crossing carrier wave i_4 shown in FIG. 1(e).

$$i'_5 = \pm 2i_1 \sin \left(\omega t - \frac{\pi}{2} \right) = \pm 2a_1 \sin \left(\omega t + \frac{2\pi}{3} \right) \\ \times \sin \left(\omega t - \frac{\pi}{2} \right) = \pm \frac{\sqrt{3}}{2} a_1 \text{ (D.C. component only)}$$

and

$$i'_6 = \pm 2i_2 \sin \left(\omega t - \frac{\pi}{2} \right) = \pm 2a_2 \sin \left(\omega t - \frac{4\pi}{3} \right) \\ \times \sin \left(\omega t - \frac{\pi}{2} \right) = \mp \frac{\sqrt{3}}{2} a_2 \text{ (D.C. component only)}$$

Thus, if one is positive, the other is negative. Therefore, it is possible, due to the polarities of R_1 and R_2 , to determine the readings of the meters MET_1 and MET_2 so that REL_1 if i'_5 is positive, and REL_2 , if i'_6 is negative, may independently operate. This is possible because the sending end modulation is a single current. Whereas, by the well-known phase reverse modulation, the phase of the output code is not determined, because a_1 and a_2 themselves become positive or negative.

In other words, it is possible to make the phase of the carrier wave generation circuit i_0 when CH_1 or CH_2 is receiving communication, and to separate them to REL_1 and REL_2 , respectively, for reception. If neither MET_1 or MET_2 operates and only MET_3 operates, then MET_3 is in the reverse direction, and it is necessary, in order to reverse SW manually, to interrupt the input (3) so as to make REL_1 and REL_2 operate. If none of the meters work, there is a fault in the line, and it is necessary to

wait until the line is restored before sending the carrier wave i_0 from the sending end for the initial phase synchronizing.

In the receiving relay circuit of FIG. 2 (b), it is also possible as shown in FIG. 3 to use, besides the polarized relays REL_1 and REL_3 , a set of relays P_1 and P_2 so as to use their contacts simultaneously.

Furthermore, since these relays are not suitable for a high-speed communication such as PCM, they may be replaced by the well-known flip-flop circuit or a regenerative repeater circuit. Consequently, SW of FIG. 2 (b) can be switched with the flip-flop output.

Next, as shown in FIG. 4, the modulators of FIG. 2 (a) may be replaced by two sets of relays REL_3 and REL_4 which perform the same operation in case of telegraph.

In other words, assuming that contacts r_3 and r_4 are operated by their respective relays, the first channel transmits the carrier wave of $2\pi/3$ when only REL_3 operates, and the second channel, that of $4\pi/3$ when only REL_4 operates. Thus, if simultaneous communications are being performed, the resultant output of branches (2) and (3) is transmitted and branch (1) is short-circuited to perform the same function as FIG. 2(a).

It is also possible as shown in FIG. 5 (b) to generate the three-phase vector carrier wave by using only one phase shifter PS_5 of $\pi/3$ phase. This is because, as shown in FIG. 5 (a), the carrier wave is obtained by combining the zero phase, the resultant of the reverse phase and the $\pi/3$ phase, and the reverse phase of the $\pi/3$ phase, and the amplitude is regulated by the attenuator.

Furthermore, the rectifiers R_1 and R_2 of FIG. 2 (b) can be omitted by, as shown in FIG. 6, using two sets of balanced modulators in opposite directions as the demodulator D_1 in the receiving end.

Alternatively, it is also possible to determine the direction of current only with R_1 and R_2 by using non-polarized relays for REL_1 and REL_2 of FIG. 2 (b) and to discriminate CH_1 and CH_2 .

According to the modulation system of this invention, the zero phase carrier wave i_0 is always transmitted except while i_1 and i_2 are simultaneously communicating, here i_0 is interrupted and $-i_0-i_3$ is transmitted, but conversely, if i_0 is always transmitted from the sending end, the receiving carrier wave is zero during the simultaneous communication, because $i_1+i_2+i_3=0$. Hence, a receiving method can be worked out in which the above is utilized to add a constant D.C. code when the receiving current is zero.

That is, as shown in FIG. 7, if the output of the band pass filter BP_2 is rectified by a rectifier $RECT$ to operate a relay REL_5 , whose biasing current is regulated so as to reverse the mark and space, then a double current is obtained from the local circuit, which can be superposed on the contact circuits of REL_1 and REL_2 of FIG. 2 (b).

Again, the multiplier and the divider circuit of the synchronizing carrier wave generation circuit can maintain, even during the instantaneous interruption of the input carrier wave or during simultaneous communication of i_1 and i_2 , the carrier wave phase i_0 during the previous independent communication, by using the well-known magnetic reactor frequency divider, parametron frequency dividers, or a triple multiplier and one-third divider circuit comprising a blocking oscillator, and tuning fork oscillator.

Again, if only one channel of i_1 or i_2 is transmitted, only two phases of the three-phase vector are utilized and the amplitudes of the transmitted vectors are constant.

In any case, since the transmission vector during the time when i_1 or i_2 is communicating, is $i_0+i_1=-i_2$ or $i_0+i_2=-i_1$ as previously stated, and is equal to the reversed phase vector of the other, the required phase

shifted wave is obtained by merely replacing the carrier wave vector of the modulator by i_1 or i_2 and reversing the phase. In this case, the output of the branch (1) of FIG. 2 (a) becomes unnecessary.

While I have described above the principles of my invention in connection with specific apparatus, it is to be clearly understood that this description is made only by way of example and not as a limitation to the scope of my invention as set forth in the objects thereof and in the accompanying claims.

What is claimed is:

1. A code transmission system for providing two binary code signal channels on separate phases of a single frequency three phase carrier wave, the third phase of which serves as a synchronizing channel, comprising means for providing three phase carrier frequency wave, means for keying two phases of said wave on-and-off in accordance with binary signals of individual channels, and means for keying off the third of said phases in response to simultaneous keying on of said two phases.

2. A system according to claim 1 further comprising means to receive said three channels, a filter for selecting waves of the frequency of said carrier, means for generating a frequency synchronous with said third phase in response to said selected waves and means responsive to said synchronous wave for discriminating the binary signals of said two channels.

3. A phase shift code transmission system for use with two multichannel binary inputs of single-current system comprising: a transmitter including means for producing three phase sinusoidal carrier signals of a single frequency and coupling means for applying said three phase signals onto a common line, said coupling means comprising means for switching on-and-off two of the three phase signals in response to said binary inputs, respectively, and means for continuously sending out the remaining one of the three phase signals as a synchronizing signal for reception: a receiver for each of said binary input signals comprising a band-pass filter rejecting all save said single frequency means for generating a receiving synchronizing signal synchronous with said remaining one of the three phase signals; and means for reproducing said binary signals in response to said receiving synchronizing signal and the received three phase signals, said means comprising a phase discriminating means including a pair of parallel oppositely polarized relays coupled to the input of said receiver and a combination of D.C. indicating means associated with said relays for discriminating the two of the three phase signals with reference to said receiving synchronous signal.

4. A phase shift code transmission system as claimed in claim 3 in which the three phases are 120° apart and the third phase is at 0° .

5. A phase shift code transmission system as claimed in claim 3 in which the means for generating a signal synchronous to the third phase comprises a frequency multiplier of three and a frequency divider of three coupled thereto.

6. A phase shift code transmission system as claimed in claim 3 in which the means for discriminating the digital information includes a pair of parallel opposite polarized relays coupled to the input of the receiver and the synchronous signal generating means.
